Primary Examiner — T. Chase Nelson*Assistant Examiner* — Jonathan J. Han(74) *Attorney, Agent, or Firm* — Edell, Shapiro & Finn, LLC(57) **CLAIM**

The ornamental design for a shoe sole, as shown and described.

DESCRIPTION

FIG. 1 is a perspective view of a shoe sole showing my new design;

FIG. 2 is a bottom plan view thereof;

FIG. 3 is a top plan view thereof;

FIG. 4 is a left side view in elevation thereof;

FIG. 5 is a right side view in elevation thereof;

FIG. 6 is a front view in elevation thereof; and,

FIG. 7 is a rear view in elevation thereof.

The shoe sole illustrated is a first embodiment showing a right-footed form of the shoe sole. A second embodiment of the shoe sole is for the left-footed form of the shoe sole, which is a mirror image of the right-footed form, is not illustrated.

The broken line illustration of environmental structure in FIGS. 3 and 4 is not part of the claimed design.

1 Claim, 7 Drawing Sheets(56)
